HERMETICALLY SEALED CONTAINER

Harry E. Townsend, Brooklyn, N. Y.; Title Guar-
antee and Trust Company executor of the es-
tate of said Harry E. Townsend, deceased

Application October 23, 1933, Serial No. 694,831

1 Claim. (Cl. 215—40)

My invention relates to hermetically sealed containers.

One of the objects of my invention is to provide a container and closure of such construction that food to be preserved can be placed in the container in an uncooked or unsterile condition, the closure hermetically sealed on the container with or without vacuum, and the sealed package subjected to cooking or sterilizing heat 10 without danger of impairing the hermetic seal or subjecting the package to excessive internal pressure.

Another object is to provide a container of the character indicated which is so constructed that 15 during the sterilizing or cooking operation, when excessive pressure is generated within the hermetically sealed package, the hermetic seal is momentarily broken to relieve the pressure and the package immediately re-sealed automatically.

Another object is to provide a construction in 20 a container and closure to be used in the indicated manner, whereby the closure may be sealed on the container without a vacuum, the sealed package subjected to sterilizing or cooking heat, and upon the cooling of the package, a vacuum or partial vacuum created therein.

Another object is to provide a package of the indicated type in which a liquid or semi-liquid content may be maintained for a predetermined 25 time at a temperature corresponding with its boiling point, without causing the contents to boil and without causing the pressure in the package to rise above a predetermined degree.

Another object of the invention is to provide 30 a novel and improved package of this character in which the closure may be easily removed and replaced on the container with or without the gasket, the closure when replaced being held by frictional engagement with the container.

I attain these and other objects by means of the construction illustrated in the accompanying drawing in which:—

Figure 1 is a side elevation of a container and closure embodying my invention with the closure shown partly in section;

Fig. 2 is a detail sectional view on an enlarged scale, taken on the line 2—2 Fig. 1, but showing the closure in the position it may assume at the beginning of the gasket compressing operation;

Fig. 3 is a view similar to Fig. 2 but showing the closure sealed on the container;

Fig. 4 is a view similar to Fig. 3 but showing the closure as it may be momentarily lifted to relieve excessive internal pressure that may be generated while the sealed package is being sub-

jected to sterilizing or cooking heat, the extent to which the closure may be so lifted being somewhat exaggerated, as shown;

Fig. 5 is a sectional view similar to Fig. 3 showing an implement in position to remove the closure from the container;

Fig. 6 is a sectional view, taken on the line 6—6 of Fig. 3; and,

Fig. 7 is a view similar to Fig. 3 of a modification of the invention.

The preferred embodiment of my invention illustrated in Figs. 1 to 6, inclusive, of the drawing, comprises a glass jar 2, a sheet metal cap 4 and an elastic gasket 6.

The jar is provided with a cylindrical mouth 15 portion 8 of considerable depth, and is further provided, at the bottom of the cylindrical portion, with a narrow horizontal shoulder 10 and a downwardly and outwardly sloping annular shoulder or face 12.

The gasket 6, which is preferably rectangular in cross-section, is positioned over the mouth portion 8 of the jar and upon the horizontal shoulder 10. The gasket is made slightly smaller in diameter than the cylindrical mouth portion 25 15 so as to cause it to tend to hug the mouth portion when placed thereon.

The cap 4 is provided with a flat top portion 14, and a skirt having a crown portion 16, an outwardly extending portion 18 and preferably 30 with a downwardly extending portion 20, terminating in the curled over portion 22. The closure can be sealed on the container by passing it over the cylindrical mouth portion 8 of the container and pressing it down on the gasket 35 seated on the shoulder 10.

Except as hereinafter described, the parts above referred to may be the same as parts of the device illustrated, described and claimed in my U. S. Patent No. 2,099,710, issued November 23, 40 1937.

One of the principal features of the present invention is the provision of means whereby the closure is yieldably held sealed on the container independently of atmospheric pressure, and, in 45 case excessive pressure is generated within the sealed package, the seal is momentarily broken to relieve the pressure and the package instantly and hermetically re-sealed.

As shown, the cylindrical mouth portion 8 of 50 the container is provided with a plurality of projections or nubs 24, which project outwardly a distance slightly less than the distance between the cylindrical mouth portion and the crown 16 of the closure. These projections are 55

preferably curved circumferentially of the jar, as shown in Fig. 6, and from a point near their tops are tapered downwardly and inwardly so that these parts of the projections form portions 5 of inverted cones, the upper portions of the projections, being beveled toward the edge of the mouth portion.

In the crown 18 of the closure there is formed 10 an inwardly projecting annular bead or groove 26, the inner diameter of which is slightly greater than the cylindrical mouth portion 8 of the container, but less than the diameter of a circle bounding the most outwardly lying portions of 15 the projections 24.

15 When the closure is forced down over the mouth of the container, the annular bead is distorted from a true circle as it passes over the most outwardly extending portions of the projections 24, and, although this distortion becomes 20 less as the closure is pushed down to sealing position, it is still present to some degree as shown in Fig. 6. The constricting influence or tension of the distorted bead, as it bears on the downwardly and inwardly tapering surfaces of the 25 projections, readily urges the closure in the downward direction with sufficient force to compress the gasket and seal the closure on the container independently of atmospheric pressure.

This construction provides the advantage that 30 the container can be filled with an uncooked or unsterilized product, the closure sealed on the container with or without a vacuum, and the sealed package subjected to cooking or sterilizing heat for any desired length of time without danger of displacing the closure or subjecting the package to excessive internal pressure. When 35 the closure is initially sealed on the container without a vacuum the head space of the package is, of course, filled with air, and it is very desirable that as much as possible of this air be expelled from the package, not only that the resulting vacuum may aid in holding the closure securely sealed on the container, but because the oxygen of the air is harmful to many food products. It may also be desirable in some cases to 45 maintain the contents of the package at a temperature corresponding with their boiling point but without permitting boiling to occur. If the contents are allowed to boil and, therefore, to 50 vaporize, some of the vapor will be forced out of the package, in consequence of which, the package will lose weight.

With the construction described it is possible 55 to expel the air from a package that has been sealed without a vacuum and then to maintain the contents at a temperature corresponding with their boiling point without causing the contents to boil. This is so, because, as the temperature of the package increases, the air in the head 60 spaces expands and the closure is lifted (Fig. 4) sufficiently to permit a portion of the air to escape, whereupon the constantly present constricting influence of the bead 26 on the projections 24 again instantly urges the closure to sealing 65 position. When enough of the air has escaped so that what remains has not enough expansive force to lift the closure, the slight pressure it exerts upon the surface of the liquid contents of the package is sufficient to prevent the 70 contents from boiling even though they may be at boiling temperature. The package remains hermetically sealed at the end of the cooking or sterilizing operation and no further attention to the seal is necessary. Of course, the contents of

a package subjected to this process are absolutely sterile.

It will be apparent that the size, spacing and inclination of the projections and the diameter of the tension bead of the closure may be varied 5 to meet different conditions. With the use of jars or tumblers having their mouth portions approximately two and one-half inches in diameter, satisfactory results have been secured with the use of six projections on the jar which are of 10 short radius in cross section and are otherwise proportioned as shown in the drawing, the bead on the cap being of proper diameter and the resiliency of the material of the cap being such as to obtain the required tension when the cap is 15 applied.

When it is desired to remove the closure from the container this may be easily done by inserting a pointed implement between the lower edge of the skirt of the closure and the downwardly 20 sloping surface 12 of the container so that its point is in position to rest on the horizontal shoulder 10, as shown in Fig. 5. In this position the point of the implement is a considerable distance above the lower edge of the skirt of the 25 closure and some distance inwardly therefrom which gives sufficient leverage so that a single upward movement of the tool will pry the closure entirely free of the container.

When it is desired to provide a closure that 30 can be used in the indicated manner and that is at the same time adapted to be re-sealed on the container without the gasket, the closure may be made as illustrated in Fig. 7. In this case, the inside diameter of the crown of the closure is 35 made slightly less than the greatest diameter of the projections 24. When the closure is so made, the frictional engagement of the projections 24 with the crown of the closure is not sufficient to prevent the tension bead 26 from forcing the 40 closure down into sealing engagement with the gasket.

As will be evident to those skilled in the art, my invention permits various modifications without departing from the spirit thereof or the scope 45 of the appended claim.

What I claim is:

The combination of a container having a cylindrical mouth portion and a gasket seating shoulder positioned a distance below the top of 50 said cylindrical portion, an elastic gasket seated on said shoulder, and a closure of resilient material having a cylindrical crown portion adapted to fit over said cylindrical mouth portion and a portion below said cylindrical crown portion 55 adapted to compress said gasket on said shoulder, said cylindrical mouth portion of the container being provided with a plurality of spaced projections having the lower portions of their outer faces tapering downwardly and inwardly, and 60 said cylindrical crown portion of the closure being provided with an inwardly directed bead having an inner diameter slightly greater than the diameter of said cylindrical mouth portion but less than the greatest diameter of said projections, whereby when the closure is positioned on the container with said inwardly directed bead engaging the downwardly and inwardly tapering faces of said projections, the constricting effect of said bead urges the closure in a 65 downward direction and holds said gasket compressing portion of the closure in yieldable engagement with said gasket.

HARRY E. TOWNSEND.
